BOILER WASHING BLOW-OFF CONNECTION

Filed Feb. 12, 1931

UNITED STATES PATENT OFFICE

BARTON P. PHELPS, OF TOPEKA, KANSAS

BOILER WASHING BLOW-OFF CONNECTION

Application filed February 12, 1931. Serial No. 515,259.

My invention relates to a blow-off connection for use in boiler washing plants and particularly a connection for use in washing plants where a plurality of boilers, such as 5 locomotive boilers, are to be blown off at the same time.

My invention has for its object the provision of a connection, intermediate of the respective boilers and the common or main 10 blow-off line, whereby the pressure energy of the blown off water and steam is converted into kinetic or velocity energy, thereby increasing flow through the main line and consequently eliminating back pressure being 15 created in the main line.

With boiler washing plants or systems as heretofore constructed, the simultaneous blowing down or blowing off of two or more locomotive boilers was inefficiently done 20 where the locomotive boilers were under different degrees of pressure.

The blowing off operation of a plurality of boilers therefore resulted in loss of time and the consequent loss of the locomotives for 25 service.

The objects and advantages of my invention will be understood and readily apparent from the detailed description of the accompanying drawing, wherein:—

30 Figure 1 is a more or less schematic view in elevation of the main part of a boiler washing system and a plurality of locomotives positioned and connected thereto, with the wash-out and fill tanks partly broken away and in section; the system being provided with my improved connections.

35 Figure 2 is a detail view, partly in section, showing my improved connection with the blow-off main or line of which only a portion is shown.

40 Figure 3 is a side elevation of portions of the blow-off lines showing the usual T-coupling heretofore employed.

45 With boiler washing systems as heretofore constructed and particularly as employed for blowing off, washing and refilling locomotive boilers, considerable difficulty was encountered in carrying out these operations at the same time with a number of locomotives. 50 That is to say, the blowing off of two or more

locomotive boilers under different degrees of pressure was impossible until the pressure in the respective boilers had become substantially equal. Consequently considerable loss of time in service of the locomotives resulted. 55 This difficulty was due to the type of connections between the respective drop lines and the common blow-off main or line, which resulted in a back pressure being set up in the blow-off main by the steam and water 60 blown off from the locomotive having the greatest degree of pressure.

In order to properly exemplify my invention, I have shown it in connection with a well known type of boiler washing system 65 as employed by railroad systems for blowing down, washing and refilling locomotive boilers; a number of locomotives being shown in elevation at A, B, C and D and all connected up with the system. 70

The locomotive indicated at A is connected by means of drop line 10 with the wash-out water main 11; locomotive indicated at B is connected by means of drop line 12 with the filling water main 13; while the two locomotives indicated at C and D are shown connected by means of drop lines 14 and 15, respectively, to the common blow-off main 16 through the medium of my improved connection indicated at 17, 17. 75

In other words, locomotives C and D are at the blowing off stage of the operation; locomotive A is at the wash-out stage of the operation; while locomotive B is being filled with heated fresh water. 80

The system as illustrated in the drawing involves a separating tank 18, generally known as the blow-off tank, to which the blow-off main 16 is connected.

In this tank the blown off water and steam 90 separate; the water being allowed to escape to the sewer by means of the stand-pipe or sewer vent 20 which has a sewer connection at bottom; drain to the sewer vent being possible through the water sealing pipe 21. 95 or direct through valve 21.

The steam from separating tank 18 passes up through pipe 22 into a heater 23 which is also provided with a make-up or fresh water line 24. 100

The steam entering heater 23 encounters the incoming cold water from line 24, thereby heating the fresh water which flows down through column or conduit 25 and discharges 5 through the opening 26 into the bottom of the inner tank 27 which is known as the filling tank. This tank is open at the top and is surrounded by the outer tank 28—on which the heater is located—and which 10 is known as the wash water tank and which in turn is provided with an overflow connection 29 with the sewer vent 20; and the wash-out water may be cooled or tempered with fresh cold water admitted by line 24^a upon 15 opening valve 24^b.

As the inner filling water tank becomes full, it will overflow into outer tank 28 and provide a supply of water for washing out the locomotive boilers; the wash-out main 11 20 being connected with the bottom of the wash-out tank by means of pipe 30; while the fill tank 27 is connected at its bottom by means of pipe 31 with the fill main 13; the wash water main 11 and the fill water main 25 13 being provided with the usual pumps as indicated at 32 and 33, for withdrawing the water from tanks 28 and 27, respectively, and forcing it into the locomotive boilers.

All of the elements heretofore referred to, 30 with the exception of the connections indicated at 17, are of usual construction, arrangement and operation and further illustration and detailed description of such elements need therefore not be entered into.

35 As heretofore constructed, the blow-off drop lines 14 and 15 were connected to the main blow-off line by the usual T-coupling 39 shown in Figure 3, so that the water and steam would pass up through the drop-lines and into the blow-off main 16 at approximately right angles. This not only resulted in quick wear of the blow-off main 16, but also produced a back pressure in a drop line 40 at a time when a number of locomotives were being blown down at the same time.

For example, with the connections as heretofore constructed and employed, if locomotive indicated at C was being blown down from a pressure of eighty pounds while the 50 locomotive indicated at D was to be blown down at the same time while at a pressure of forty pounds, the blowing down of locomotive D could not be accomplished until locomotive C had been reduced to the pressure of locomotive D. In other words, when a locomotive with a high pressure was connected to the blow-off line the blowing down of other locomotives connected up and of less pressure was delayed until the pressures were 55 equal, thus incurring considerable loss of time; also repairs to the blow-off main are necessary very frequently because of the wearing away of the line at the drop line connections by the water and steam under 60 pressure.

With my improved drop line connection with the main blow-off line, as shown at 17, these difficulties and objections have been overcome. My improved connection as exemplified in the drawing consists in providing the blow-off drop-lines with a pipe extension 34 beyond the check-valves 35 and usual gate valves 36.

The pipe extension 34 is arranged substantially parallel with the main blow-off line 75 16 and provided with a gradual ogee curve at 37 toward and into the main line 16. The main line 16 is provided with a suitable opening to receive the curved section 37 of the pipe extension 34, arranged so as to permit the inner or free end of the curved section 37 to extend in the direction of water and steam flow through main line 16 as shown at 38 in Figure 2. The curved section is 80 preferably of such construction that the inner free end 38 extends a slight distance lengthwise within the main line as shown. The section 37 is then securely welded to the main line 16.

The end 38 of the pipe extension or connection serves as a velocity nozzle providing velocity energy which produces an increased flow in the blow-off main or line 16.

In actual practice my improved connection 95 has the effect, with locomotives C and D of unequal pressures, of reducing the time of blowing down the locomotive D of assumed lower pressure as in the example heretofore given.

I prefer to make a welded connection between the main blow-off line 16 and the curved section 37, but other suitable water and steam tight connections may be made if possible; and it will be understood that any 100 number of drop-lines may be connected into the main blow-off line 16 in keeping with requirements.

The specific disclosure of the invention is believed to be the best embodiment which has been described in terms employed merely as terms of description and not as terms of limitation, as structural modifications may be made without, however, departing from the spirit of my invention.

What I claim is:

1. A boiler washing blow-off connection comprising, in combination with a water and steam receiving main line, and a drop line adapted to be connected to the boiler to be blown down, a connection between said main line and said drop line having a portion disposed substantially in alignment with the discharge end of the drop line and parallel with the main line and a second off-set portion arranged substantially parallel with the 120 first portion and disposed within the main line substantially parallel therewith in the direction of flow through said main line.

2. A boiler washing blow-off connection comprising, in combination with a main line 130

for receiving water and steam under pressure and a drop line between said main line and the boiler to be blown off, a connection intermediate of the two lines having one portion in substantial alignment with the discharge end of the drop line, a gradual curved portion sloping toward the main line and extending therein and a discharge portion within the main line disposed lengthwise therein in the direction of flow through said main line, the juncture between the curved portion and the main line being hermetically sealed.

3. A boiler washing blow-off connection comprising, in combination with a main line for receiving water and steam under pressure and a line between said main line and the boiler to be blown off, a conduit between the two lines involving a straight portion having a curved connection with the discharge end of the second mentioned line and disposed substantially parallel with the main line, an intermediate portion gradually curving toward and in the general direction of the main line and extending therein and sealed thereto and a third discharge portion extending lengthwise within the main line in the direction of flow through the main line, and means for controlling the flow from the second mentioned line into said connection.
